UNITED STATES PATENT OFFICE.

GEORGE E. M. STUMPP AND KARL KAMMANN, OF SOUTHAMPTON, NEW YORK.

DESIGN FOR A FLOWER-HOLDER.

53,669.

Specification for Design.

Patented July 29, 1919.

Application filed March 12, 1919. Serial No. 282,218. Term of patent 7 years.

To all whom it may concern:

Be it known that we, GEORGE E. M. STUMPP and KARL KAMMANN, both citizens of the United States, residing at Southampton, in the county of Suffolk and State of New York, have invented a new, original, and ornamental Design for a Flower-Holder, of which the following is a specification, reference being had to the accompanying drawing, forming part thereof.

The figure is a perspective view of a flower holder, showing our new design.

We claim:

The ornamental design for a flower holder, as shown.

GEORGE E. M. STUMPP.
KARL KAMMANN.
